FLAME BLOCK FOR FURNACES

Sylvan N. Levy, Arden, Del.

Application May 15, 1939, Serial No. 273,768

6 Claims. (Cl. 158—1)

This invention relates to flame controllers or distributors for use in any and all types of furnaces, lead pots, etc., where a plume or other type of flame having a generally circular cross sectional form is normally projected from the tip or mouth of a gas, oil, or other type of burner, into a heating chamber in which a flat cross sectional or ribbon type of flame may be more desirable, as in the case of the heat treating 5 furnace disclosed in my copending application, Serial No. 243,826, filed December 3, 1938.

The present invention relates more specifically to a flame distributor or controller in the form of a refractory tile or block adapted to be set in and 10 to form a part of the inner refractory wall of a furnace, etc., which wall may be either flat or circular, as in the case of the furnace disclosed in the aforesaid copending application. In the furnace of said application, and in the 15 present instance, the refractory wall is of the circular type. The flame block constitutes a segmental portion of the wall and is provided on its outer arcuate face with a flame inlet opening of one cross sectional form and on its 20 concaved face with a discharge opening of different cross sectional form. The inlet and discharge openings are connected by and through a transitional channel in which the cross section thereof changes progressively and smoothly 25 from the cross sectional form of the inlet opening to the cross sectional form of the discharge opening, as will be more fully disclosed herein- 30 after, reference being had to the accompanying drawings, of which:

Fig. 1 is a perspective view of a preferred form 35 of flame block made in accordance with the present invention, viewing the convexed side of the block in which the inlet opening is formed;

Fig. 2 is a perspective view of the block viewing 40 the concaved face thereof, in which the discharge opening is formed;

Fig. 3 is a sectional elevation taken on the line 3—3, Fig. 1;

Fig. 4 is a sectional elevation taken at right 45 angles to the plane of the section of Fig. 3, on the line 4—4, Fig. 3;

Fig. 5 is an outside view looking in a direction 50 perpendicular to the plane indicated by the arrows 5, 5, in Figs. 3 and 4 respectively;

Fig. 6 is a cross sectional view taken on the lines 6—6, 6—6, in Figs. 3 and 4 respectively;

Fig. 7 is a cross sectional view taken on the lines 7—7, 7—7, Figs. 3 and 4 respectively; and

Fig. 8 is a cross sectional view taken on the 55 lines 8—8, 8—8, Figs. 3 and 4 respectively.

As shown in Figs. 1, 2 and 5 the flame block 1, is composed of any suitable refractory material, such, for example, as that known as Mullite. However, any suitable fire brick material may be employed. The block 1 is in the form of a segment of a ring, having predetermined radial thickness and predetermined width.

Formed on and projecting outwardly from the convexed surface 2 of the block 1 is a boss 3. The boss or other protuberance 3 has a flat surface 4 disposed in a plane arranged at an intersecting angle to the planes of the convergent radial end surfaces 5 and 6 of the block 1. Formed in the flat surface 4 is a flame inlet opening 7 of any suitable predetermined contour. In the present instance, as shown in Fig. 5, the flame inlet opening 7 is of a substantially circular contour.

The inner or concaved face 8 of the block 1 is provided with a discharge opening 9 which is of a different contour than the inlet opening 7. In the present instance, the discharge opening is of a general rectangular form.

The inlet opening 7 and the discharge opening 9 are connected by a transitional channel 10, which, as shown in Figs. 6, 7 and 8, changes gradually and smoothly from the contour of the inlet opening 7 to the contour of the discharge opening 9, whereby a flame projected into the inlet opening 7, assuming the flame to be of the general circular plume type, will pass into the transitional channel 10 and engage smoothly curving side walls 11, 11 of the channel 10. Such engagement with the convergent side walls 11, 11 will cause the flame to be thinned out in one direction from its original circular cross sectional form and measurements, to a thickness corresponding to the width or shorter dimension of the rectangular channel, at the plane indicated by the lines 8—8, in Figs. 3 and 4. Thinning of the flame in the one direction causes the flame to spread in a right angle direction, substantially into engagement with the end walls 12, 12 of the channel 10, as shown in Fig. 4 and Fig. 8.

From the plane indicated by the line 8—8 toward the concaved face 8 of the block 1, as shown in Fig. 3, one wall 11 of the channel 10 curves or flares outwardly from the opposite wall of the channel 10, as indicated at 13. In the present instance, although not necessarily, the flaring portion 13 intersects with the radial end wall 6 and the concaved face 8 at the common intersection of these two outer walls of the block 1. The second wall 11 of the channel 10

flares in the opposite direction to the flare 13, as indicated at 14, and curves outwardly from and beyond the concaved face 8 to form one edge of a flame lip 15.

5. The flame lip 15 extends completely across the channel 10, and beyond the end walls 12, 12 thereof, as clearly shown in Fig. 2. The outer surface 16 of the lip 15 converges toward and blends into the concaved face 8 of the block, 10 between the discharge opening 9 and the radial end 5 of the block.

The transitional channel 10 is designed and proportioned so as to eliminate choking of the flame which would tend to create a back pressure 15 in the channel and a flare-back of the flame toward the inlet opening 7 thereof. For this purpose the cross sectional area of the channel, at the plate 8-8, Figs. 3 and 4, is first calculated to meet the fuel requirements of the 20 furnace, or its proportional share thereof in the case of furnaces employing a plurality of flames. With this controlling area established, the cross sectional area of the channel at all planes intermediate the plane 8-8 and the plane 5-5, 25 in which latter the inlet opening 7 is formed, is never permitted to be less than the cross sectional area of the channel at the said controlling outlet plane thereof, i. e. at the plane 8-8.

30. As a matter of illustration, if the cross sectional contour of the channel 10 at the plane designated on the drawings as the plane 8-8, would have an area of approximately 3.09 square inches, the area of the inlet opening 7 at the 35 plane 5-5, would be approximately 4.13 square inches, the area of the channel at the plane 7-7 approximately 4.5 square inches, and the area at the plane 6-6 approximately 5.4 square inches. Thus, it will be seen that the area 40 at each of these planes would exceed the area of the controlling cross sectional plane 8-8.

The above noted increased areas at the planes 6-6 and 7-7 respectively, are due to the smooth stream-lining of the walls 11, 11 and 12, 12, of 45 the channel 10, from the substantially circular inlet opening 7 to the substantially rectangular discharge opening 9 provided for preventing impingement of the flame projected into the flame receiving opening 7 against any abrupt surfaces 50 which would tend to deflect the flame backwardly toward the opening 7. The shape of the interior walls of the channel 10 provides, at all points, impingement surfaces which tend to 55 change the cross sectional shape of the flame and direct the flame toward the discharge opening 9.

Having once established the correct controlling area and cross section of the channel 10 at the plane 8-8, the burner which projects the 60 flame into the inlet opening 7 is regulated so that its flame volume does not exceed the flame requirement for substantially filling the channel 10 at the controlling plane 8-8.

65. The stream-lining of the walls of the channel, as noted above, prevents the formation of what are known as hot-spots, which tend to burn out the fire brick in the walls of the flame channel as would result from impingement of the flame 70 against any retarding abutments in the walls of the channel.

It will be understood that the areas and dimensions given above are provided for the purpose of 75 illustration only, to show a relationship between the areas at the various planes along the chan-

nel, and that these measurements etc. are not to be taken as any literal limitations.

From the above, it will be clear that the transitional channel 10 by changing its cross-sectional contour progressively between the flame inlet opening 7 and the flame discharge opening 9 will convert a flame projected into the inlet 7 from its original cross sectional shape to the different cross sectional shape of the discharge port 9, which, in the present case is rectangular 10 to effect discharge of a flat ribbon-like flame into the furnace.

From the above it will also be clear that in cases where the flame block is built into a furnace wall of the circular type, as disclosed in the 15 aforementioned copending application, the arcuate flame lip 15, in addition to thickening and thereby strengthening the block at the acute angle between the concaved face of the block and the one wall of the transitional channel 10, serves, together with the arcuate surface 13 of the opposite wall of the transitional channel 10, to direct the flame into the interior of the furnace in such a manner that the flame will hug 20 the wall of the combustion chamber substantially as disclosed in the aforementioned copending application.

I claim:

1. A flame block having a flame inlet at one 30 side, a flame outlet at the opposite side, a flame channel extending through the block from said inlet to said outlet at an angle to and intersecting said opposite sides of the block, and a flame lip at the intersection of one wall of said channel 35 with one face of said block, said lip extending beyond said face of the block and having an outward then inwardly curving surface blending into said wall and said face respectively.

2. A flame block having a flame inlet at one 40 side, a flame outlet at the opposite side, a flame channel extending through the block from said inlet to said outlet at an angle to and intersecting said opposite sides of the block, a flame lip at the intersection of one wall of said channel 45 with one face of said block, said lip extending beyond said face of the block and having an outward then inwardly curving surface blending into said wall and said face respectively, the opposite wall of said channel at said outlet curving outwardly in the opposite direction from the curvature of said lip and blending into said face of the block.

3. A flame block of concavo-convex cross-sectional form having a flame inlet of predetermined contour and predetermined area at its concaved side, a flame outlet of different contour and lesser area at the concaved side of the block, a transitional channel extending through the block from said inlet to said outlet and progressively changing in cross-sectional contour from the contour of said inlet to the contour of said outlet and a flame lip at the intersection of the concave face of the block and one wall of said channel disposed at an acute angle to said concave face of the block, said lip projecting outwardly beyond said concave face.

4. A flame block of concavo-convex cross-sectional form having a flame inlet of substantially circular form at the concaved side of the 70 block, a flame outlet of substantially rectangular contour at the concaved side of the block with the longer dimension of the rectangle extending longitudinally of the block, a transitional channel connecting said inlet to said outlet and pro- 75

gressively changing in cross-sectional contour from the contour of said inlet to the contour of said outlet, said channel extending through said block at an angle to and intersecting said concaved and convexed sides of the block and having one wall curving outwardly from one longitudinal side of said outlet and blending into said concaved side of the block, and a flame lip along the opposite longitudinal side of said outlet and projecting beyond said concaved side of the block with a surface curving outwardly then inwardly and blending with the wall of the channel at the second longitudinal side of said outlet and with said concaved side of the block respectively.

5 15. 5. A flame block of concavo-convex cross-section and of rectangular outline on each of the concave and convex faces respectively thereof to form a rectangular segmental section of a cylindrical refractory furnace wall, a boss formed on the convex face of the block and comprising an outer end face disposed in a plane intersecting said convex face with a circular flame inlet formed in said end face, a flame channel formed in and extending completely through said block and said boss about an axis coincident with the axis of said inlet perpendicular to the plane of said end face and intersecting the concave and convex surfaces of the block, a rectangular flame outlet symmetrically disposed about said channel axis at the intersection of said channel axis and the concave face of the block with the longer dimension of said outlet disposed longitudinally of the block, said channel connecting said inlet and said outlet and changing progressively by constantly varying cross-sectional contour from

10 20 25 30 35

circular shape of the inlet to the rectangular shape of the outlet.

6. A flame block of concavo-convex cross-section and of rectangular outline on each of the concave and convex faces respectively thereof to form a rectangular segmental section of a cylindrical refractory furnace wall, a boss formed on the convex face of the block and comprising an outer end face disposed in a plane intersecting said convex face with a circular flame inlet formed in said end face, a flame channel formed in and extending completely through said block and said boss about an axis coincident with the axis of said inlet perpendicular to the plane of said end face and intersecting the concave and convex surfaces of the block, a rectangular flame outlet symmetrically disposed about said channel axis at the intersection of said channel axis and the concave face of the block with the longer dimension of said outlet disposed longitudinally of the block, said channel connecting said inlet and said outlet and changing progressively by constantly varying cross-sectional contour from the circular shape of the inlet to the rectangular shape of the outlet, a flame lip along one longitudinal edge of said outlet and curving outwardly therefrom and beyond the concave face of the block, then inwardly in a reverse curve, bending into said concave face, the interior wall of the outlet adjacent the opposite longitudinal edge thereof curving in the opposite direction from said outward curvature of the lip and blending into said concave face of the block.

SYLVAN N. LEVY. 35
